Application September 27, 1939, Serial No. 296,844

22 Claims. (Cl. 271—28)

This invention relates to sheet feeding mechanisms and more particularly to devices for separating individual sheets from a pile and forwarding them to printing presses, folders, slitters or other machines.

5 The general object of the invention is the provision of an improved sheet feeder of the type described which embodies novel features pertaining to the more efficient separation of the successive top sheets individually from the pile, the maintaining of the remaining sheets of the pile in properly stacked condition, and the forwarding of the separated sheets in proper alignment to the machine to be fed.

10 Although the broad principles of the invention are applicable to sheet feeders of widely varying types, for purposes of illustration the preferred embodiment is shown and described in the present specification as incorporated in a sheet feeder of the kind which forms the subject of the copending application of David P. Sanford, Serial No. 232,443, filed September 29, 1938.

15 The sheet feeder described in that application is one which is readily adjustable to feed sheets singly and in spaced relation, or to effect what is known as "stream feeding," that is, forwarding the sheets in a continuous line with each sheet overlapping the adjacent edge of the next succeeding one. This feeder is provided with a hold-down member disposed adjacent the forward portion of the pile, and a suction gripper which operates above the pile to withdraw the successive top sheets from beneath the hold-down member and move them forwardly to the conveyor which carries them to the printing press, folding machine, cutter, or other instrumentality in conjunction with which the feeder is employed.

20 As in most devices of this kind, the level of the top of the pile is maintained by means of automatically operated pile elevating mechanism. Also, in the illustrative example, the sheet lifting or separating function is performed by the same gripper member which moves the sheet forwardly to the conveyor, although certain features of the present invention are not limited to use with this

25 class of feeder.

The separation of the uppermost sheet of the pile from the underlying sheets is greatly facilitated by the winding operation which comprises directing blasts of air against the rear edges of a number of the uppermost sheets, in order to separate or "fluff up" these sheets and to lift the top sheet toward the suction gripper so that it may be readily engaged by the gripper as it descends. The air blast's further function to float

each sheet, after its separation from the pile, forwardly to the conveyor, the suction gripper having engagement with the rear edge of the sheet during a portion of its travel, and thus controlling its rate of movement, but the blasts being active to facilitate the actual introduction of the leading edge of the sheet into the conveyor, maintaining this leading edge at such elevation that it passes freely over the holding-down member at the front of the sheet.

10 In the operation of many prior machines of this type, it has been the common practice to provide a continuous blast of air under moderate pressure for separating and floating the sheets, this air being taken from the exhaust side of the 15 pneumatic pump or blower which produces the vacuum for the suction grippers. In such devices, the pressure of the blast drops off somewhat at the time the gripper seizes a sheet due to the decrease in the available supply of air through 20 the intake of the pump. For some sizes and grades of stock, this may not result in any appreciable change in feeding efficiency, but where sheets are large or curled, or where conditions 25 may be otherwise difficult, it is a decided disadvantage.

On the other hand, however, it is not generally desirable or feasible to use a heavy continuous blast to accomplish the stated functions for various reasons. A continuous blast of too great intensity may cause the leading edge of the top sheet to be lifted too forcibly against the front guiding and forwarding elements and to cause buckling during feeding. Furthermore, too heavy a blast would tend to cause the rear end portion 35 of the top sheet to be elevated too far for effective gripping by the suction devices.

40 I have found, however, that these difficulties may be obviated and the separation and feeding of the sheets facilitated by the provision of an air blast of increased intensity for a short period of time just prior to the gripping of the sheet by the suction devices. This high-pressure blast may be supplied by means of an intermittent impulse applied to the regular air blast delivered through 45 the ordinary winding jet, but it is preferably delivered through supplemental or auxiliary jets and taken from a source which is independent of the pump or blower for supplying the regular blast and suction.

50 With this arrangement, the sudden puff or extra heavy impulse of the blast for the short period of its duration will definitely and positively separate the uppermost sheets of the pile against any tendency to adhere together by reason of 55

- static charges or otherwise; and, furthermore, there is no danger of unduly elevating the rear edge of the sheet because at the time the increased impulse is given the grippers are disposed above the rear margins of the sheet and will prevent any excessive lifting or bending thereof. This additional puff is very effective in performing this function and it is not of long enough duration to cause detrimental fluttering of the sheet which might be occasioned by a continuous additional heavy air supply, and this puff serves to positively introduce an air film between adhering sheets, which film can easily be maintained by means of the ordinary air supply.
- One feature of the present invention resides in the employment, for this secondary supply, of air under pressure obtained from the buffer cylinders provided in presses of the reciprocating bed type to cushion the bed at the ends of its strokes. The particular timing of the blast received from these cylinders can be utilized to eliminate the necessity of using specially synchronized machine-operated air valves for this purpose.
- Another object of invention is to provide in a feeder of this type, a single flexible rear edge gripper which will permit self-centering or aligning of the sheet by its contact with the guiding and forwarding mechanism at the forward edge thereof.
- A further object of invention is the provision of automatically operated means synchronized with the feeding mechanism for intermittently striking or tamping the rear ends of the uppermost remaining sheets on the pile after the top sheet has been fed, to ensure the maintenance of the edge alignment of the pile of sheets.

Other objects and features of novelty relating to the separation, forwarding, guiding, aligning, and other treatment of the individual sheets and of the pile, will be apparent from the following specification when read in connection with the accompanying drawings in which certain embodiments of the invention are illustrated by way of example.

45 In the drawings:

Figure 1 is a view in vertical longitudinal section of a sheet feeder embodying the principles of my invention;

Figure 2 is a plan view of the feeder head of the mechanism shown in Figure 1;

Figure 3 is a view in rear elevation of the same;

Figure 4 is a vertical longitudinal sectional view of the feeder head taken substantially on line 4-4 of Figure 2;

Figure 5 is a transverse sectional view taken substantially on line 5-5 of Figure 4;

Figure 6 is a vertical sectional view taken substantially on line 6-6 of Figure 5;

Figure 7 is a transverse vertical sectional view through the primary air blast device taken substantially on line 7-7 of Figure 4;

Figure 8 is a horizontal sectional view through both blast nozzles and taken substantially on line 8-8 of Figure 4;

Figures 9, 10, 11, 12 and 13 are fragmentary views of the feeder head and associated portions of the feeder shown mainly in side elevation, and illustrating successive positions of the various operative parts during the sheet feeding cycle;

Figure 14 is a diagram showing the timing and relative intensity of the main and auxiliary blasts;

Figure 15 is a graph showing the path of travel of the sheet gripping element of the feeder;

Figure 16 is a somewhat diagrammatic view

partly in side elevation and partly in vertical longitudinal cross section showing portions of a reciprocating bed printing press with a sheet feeder embodying the principles of the present invention applied thereto; this view also showing in diagrammatic fashion the manner of utilizing the bed buffer arrangements of the press for providing the auxiliary winding blast; and

Figure 17 is a diagrammatic view indicating another means for providing the intermittent auxiliary blast.

In order to facilitate an understanding of the invention, reference will be made to the several embodiments thereof illustrated in the accompanying drawings and specific language is employed to describe the same. It will nevertheless be understood that no limitation of the scope of the invention is thereby intended, various further alterations and modifications being contemplated such as would occur to one skilled in the art to which the invention relates.

The pile supporting and sheet separating and forwarding mechanism are mounted on a supporting frame comprising two parallel side frame members one of which is indicated at 10 in Figure 1 of the drawings, together with suitable cross braces. A vertically movable pile elevator 11 is guided between the side frame members and supports the pile board 12 upon which the pile P rests during the feeding of the sheets from the top thereof. The elevator 11 is raised and lowered by means of the chains 13 which pass around suitable pulleys or sprockets at the upper and lower ends of the device as in the usual construction of this type. Details of one pile elevating device of this type may be found in the copending application to which reference has already been made. An upper transverse shaft 14 extending between the side frames 10 serves to support the elevator chains and a portion of the driving gear 40 for the elevator is shown at 15 together with a portion of a ratchet mechanism 16 by means of which the pile may be gradually advanced.

A feeder head indicated generally by the reference character A is disposed above the rear portion of the pile and embodies a suction gripper member 20 for separating and forwarding the sheets.

Within the housing structure B mechanism is provided for operating the feeding devices and this housing is supported upon a cross bar 22

extending between the side frame members 10, and also upon the shaft 14 and the cam shaft 23

the function of which will be later described. At the forward end of the feeder conveyor mechanism indicated generally by the reference character C serves to transfer the sheets from the feeder

to the printing press, folder or other machine to which the sheets are to be fed. A forwardly projecting frame 25 carried at its rear end upon the cam shaft 23 serves to provide supporting means

for the feed board 26 down which the sheets move either in spaced sequence or in overlapping or stream formation depending upon certain adjustments of the feeder such as described in the copending application. The sheets are carried

down the feed board upon the endless conveyor tapes 27 which are suitably supported at their forward ends (not shown) and at the rear ends

thereof they pass around the pulleys or feed wheels 30 which are carried upon the transverse

shaft 31. A drop roll 32 cooperates with the feed roll 30 and for this purpose is pivotally mounted

as at 33 and urged downwardly toward contact with the feed roll by means of the spring 34. An upper guide member 35 is provided adjacent the

bite between the feed and drop rolls and a lower inclined guide member 36 disposed adjacent the front edge of the pile. A hold-down member 40 pivoted as at 41 to a portion 42 of the supporting frame is provided with a tapered point 44 which rests upon the front edge of the pile P. In the form shown the hold-down member 40 also provides a pile elevator gauge or feeler as described in the Sanford application, but within the scope 10 of the present invention the hold-down may be of any type whatsoever.

From the preceding description, it will be readily seen that the function of the feeder mechanism is to separate the top sheet S from the remaining sheets of the pile by gripping it adjacent the rear edge thereof, then moving the sheet rearwardly so that its forward edge moves from beneath the hold-down element 40 and then to slide the sheet forwardly over the guide 36 and 20 between the rolls 30 and 32 so that it may be carried down the feed board by the endless tapes 27. The mechanism for effecting these operations will now be described in detail.

The housing B for the driving parts of the mechanism comprises essentially a vertically disposed plate or flat casting extending in parallel relation with the side frame members 10 and positioned approximately midway between these members. Secured to the lower horizontally extending margin of the housing B is a supporting bar 45 which overlies the pile board 12 and extends for some distance rearwardly thereof. The supporting bar 45 is preferably rectangular in cross section and serves to support the feeder 30 head A. The feeder head comprises a frame casting 50 which comprises spaced parallel plates 52 and 53, the plate 52 extending rearwardly for a considerable distance. The two plates are connected by the horizontal web 51 at the forward 35 end of the casting, all as clearly shown in Figures 2 and 3 of the drawings. Extending laterally from the rear end of the plate 52 is a transverse web portion 54 which is connected with the forward portion of the casting adjacent the short side plate 53 by means of a curved bar 55 forming a part of the casting and functioning as a cam track as will be later described. Projecting laterally from the short side plate 53 is a recessed portion 56 provided with overhanging gibs 57 and 40 adapted to receive the supporting bar 45. A similar projection 58 extending from the web 54 and provided with a groove and gibs also is adapted to receive a portion of the bar 45 in order to provide additional support to the rear 45 end of the feeder head casting 50. The frame 50 slides freely upon the support 48 and may be adjusted longitudinally thereon by means of suitable fastening elements such as set screws or the like.

The mounting of the mechanism of the feeder head A and its operative connections with the driving mechanism supported by the housing B is such that the sheet gripping and forwarding mechanism may be operated regardless of the adjusted fore and aft position of the feeder head with respect to its support 48, all as will be apparent as the description proceeds.

The path of movement of the sheet engaging gripper element 20 is indicated in the diagram in Figure 15. From the point a which is the lowermost position of the gripper and the one at which contact is made with the top sheet, the gripper element moves vertically upwardly a short distance to the point b from which point it is rocked rearwardly to the point c of the diagram whereby

the sheet is withdrawn from beneath the front hold-down member. Then the gripper moves forwardly through a long arc to the point d at which the suction is cut off and the sheet is freed for forwarding movement by the conveyor mechanism C. It will be seen from this brief description of the path of the gripper member, that the mechanism for manipulating the gripper is necessarily designed to move it in both horizontal and vertical directions.

Referring more particularly now to Figures 2-6 inclusive of the drawings, it will be seen that there is provided a rocker lever 60 pivoted upon a cross shaft 61 extending between the walls 52 and 53 of the feeder head frame. The forward 15 arm of the lever 60 is provided with an abutment 63 which in its downward movement is adapted to strike a stop portion 64 formed on the web 51. The lever is urged to rotate in this clockwise direction as shown in Figure 4 by means of the 20 spring 65 connected with a pin 66 extending from the end of the rocker lever 60 and also with a transversely extending pin 68 secured to the lowermost forward portion of the frame 50 (see Figure 1). A pivot pin 70 passes through an 25 opening in the rearward end of the rocker arm or lever 60 and projects laterally upon either side thereof to be received within registering openings in the bifurcated end of a generally vertically disposed swinging carrier 75. The carrier 75 30 is adapted to oscillate between the intermediate portion of the side wall 52 and the cam bar and connecting member 55 of the frame 50, and at the lower end of the carrier an enlarged hollow boss 76 is formed for the reception of the suction 35 gripper element designated generally by the numeral 20. The gripper element 20 comprises a substantially cylindrical element 78 and a downwardly extending threaded nipple 79 and an offset arm 80. The rubber suction cup 82 is secured 40 to the nipple 79 by means of the flanged sleeve 83 as clearly shown in Figure 5. The arm 80 is provided with a pin 84 upon which a cam roller 85 is adapted to rotate. A hollow headed bolt member 86 passes concentrically through the 45 cylindrical member 78 and enters the opening in the boss 76 at the lower end of the carrier 75. The bolt 86 is pinned as at 87 to the carrier and is provided with right-angled passageways 88 providing communication with the nipple 79 and the 50 suction cup 82. A pipe 90 extends from the boss 76 and provides a connection for a coupling hose leading from the source of suction.

The pin 84 is connected by means of the spring 92 with a lug 93 formed on an intermediate portion of the carrier 75 and serves to urge the suction gripper 20 in a counterclockwise direction as viewed in Figure 4. A projection 95 on the cylindrical member 78 cooperates with an abutment device 96 disposed on the carrier 75 in 55 order to limit this counterclockwise movement. One of the bifurcations of the upper end of the carrier member 75 is extended forwardly to form an arm 97. This arm is provided with an opening in its end adapted to rotatably receive the pin 65 98 extending from the slotted block 99. The slotted block is adapted to operatively engage a horizontal bar 100 which extends rearwardly from the housing B and serves to actuate the separating and forwarding mechanism.

A hollow boss 101 is formed at an intermediate point on the carrier 75 and receives a pin 102 which carries upon its end a roller 103. This roller is disposed generally beneath the operating bar 100 but is adapted to be contacted thereby for 75

effecting certain movements of the carrier and suction gripper. Upon the inner face of the wall 52 there is formed a projection 106 having a plane rearwardly projecting surface adapted to cooperate with a similar projection 108 formed on the carrier arm 75. Secured as at 110 to a downwardly projecting flange 111 adjacent the transverse web 54 of the feeder head casting 50 there is secured a cross bar 112 which extends from one side to the other of the space between the side frames 10 and beyond each side of the pile P. Adjacent the ends of this bar 112 there are provided corner guides 114 having pile engaging blades 115 and 116 for the alignment of the uppermost sheets of the pile during the feeding operation. These guides also cooperate with the feeder mechanism in a manner which will be later described.

The vertically moving horizontal actuating bar 110 is oscillated vertically by means supported from the housing B pivotally mounted upon pins 120 and 121. Fixed in this housing are two bar operated levers, a three-armed lever 122 mounted upon the pin 120 and a three-armed lever 123 mounted upon the pin 121. Parallel downwardly extending arms of these levers are connected by a link 124 so that the levers are constrained to simultaneous rocking movements through equal angles. One arm of lever 122 is pivotally connected to actuating rod 100 at 125 and an arm of the lever 123, of the same length and inclined at the same angle, is pivotally connected to bar 100 at 126. Hence it is clear that rocking movements of these levers must be equal and simultaneous and will bring about substantially vertical rising and falling movements of the actuating bar 100. A spring 127 acting upon an upwardly extending arm of lever 122 tends to rock both levers in a clockwise direction (Figure 1) and causes the cam follower 128 rotatably mounted upon the upwardly extending arm of lever 123 to bear at all times against a cam 130 fixed upon the cam shaft 23 previously referred to. Rotation of the cam shaft 23 and the cam 130 therefore brings about rocking movements of the levers just described and the necessary rising and falling movements of the actuating bar 100 for the gripper manipulating means.

The operation of the suction gripper element will now be described more particularly in connection with Figures 9-13 inclusive of the drawings which show the gripper and other associated mechanism in successive positions which they occupy during the feeding cycle.

In the position shown in Figure 9 the uppermost sheet S of the pile P is still gripped at its forward edge by means of the hold-down member 40 and the rearward portion is floating upon the air provided by the winding devices which will be described later in connection with another important phase of the present invention. The operating bar 100 is at an intermediate point in its downward movement. Further downward movement of the bar from this position will bring the suction gripper 20 into gripping contact with the sheet S. It will be noted that the rocker arm 60 has been moved slightly in its counterclockwise direction and that there is a slight gap between the abutments 63 and 64, this movement being of course against the tension of the spring 65. Further downward movement of the bar 100 not only carries downwardly the block 99 attached to the arm 97 of the carrier 75 but also through its contact with the

roller 103 moves the whole carrier 75 bodily downward in a substantially vertical path (this path being represented by the portion b, a in the diagram of Figure 15). This short vertical movement is permitted by the swinging of the rocker arm 60 about its pivot 61 and may be limited by the contact of the roller 103 with the upper side of the cam bar 55. This lowermost position, designated a in the diagram in Figure 15, is shown in Figure 10 of the drawings. The suction gripper 20 has made contact with the uppermost sheet S and the sheet is seized by means of the suction that is made effective by appropriately timed valve mechanism at this point.

From this point the bar 100 begins to move upwardly and the path of the mechanism is retraced to the point shown in Figure 9. At this point (b) the cam roller 85 on the gripper 20 strikes the lower curved cam surface of the cam bar 55 as indicated in Figure 9 and further upward movement of the bar 100 serves to rock the gripper 20 rearwardly against the tension of the spring 92 and thus pulls the sheet S out from beneath the forward hold-down member 40. At the end of this rearward movement as shown in Figure 11 and indicated at point c in the diagram in Figure 15) the rocker arm 60 has moved to its limit in a clockwise direction and the abutments 63 and 64 are in contact. From this point also further upward movement of the actuating bar 100 will carry it away from the roller 103 on the carrier 75 and through the arm 97 the bar 100 will rock the carrier 75 toward the right in the figures of drawing until it reaches the position shown in Figure 12 of the drawings and designated d in Figure 15. During this forward swing the roller 103 moves along the curved under-surface of the cam bar 55 and this surface is so shaped as to move the gripper 20 into substantially vertical position above the sheet. This position shown in Figure 12 represents the uppermost position of the bar 100 and the extreme forward position of the gripper. At this point the suction is automatically cut off and the sheet is moving forwardly under the control of the conveyor mechanism C. The gripper 20 moves through substantially the same path during the return portion of the cycle, one intermediate position thereof being shown in Figure 13 of the drawings. The cooperating abutments 106 and 108 on the wall 52 and the carrier 75 respectively serve to maintain the rearward position of the carrier 75 during its raising and lowering movement and permit the forward swing of the carrier 75 only when its upper limit of vertical movement has been reached at which point the rocker arm 60 reaches the limit of its clockwise motion.

The operation of this gripping mechanism as thus described and illustrated herein, is very similar to the corresponding device in the Sanford application referred to, but in this case only one gripping element 20 is employed and this element is substantially centered with respect to the pile of sheets being fed. The advantage in the use of a single gripper element, the suction cup 82 of which is made of a flexible material such as soft rubber, lies in the automatic straightening and registry of the sheets as they are fed to the conveyor mechanism. In the case where two or more grippers are employed for seizing the rear edge of the sheet it is found that the sheet is held rather positively and rigidly and if the front edge of the sheet was inadver-

tently presented to the feeding mechanism at an angle the sheets fed in this manner would go down the feed board out of square and would cause poor registry, batters, and other difficulties.

5 On the other hand, when a single rotatably flexible suction gripper is employed as in the present case the sheet is allowed a small amount of flexibility of movement and if the front edge is askew it will tend to right itself and return 10 to a squared position by the resistance encountered at the feed rolls and front guiding mechanism and will result in much more consistent and regular feeding.

Another feature of the present invention comprises a movable sheet positioning or confining device which is adapted to strike the rear edge of the uppermost sheets of the pile and administer a tapping or tamping action thereto in a forward direction in order to maintain the rear edge 15 alignment of the sheets. This tapping is effected intermittently and is timed by the movement of the suction gripper carrier 75. A downwardly projecting blade 140 is carried by the pivoted block 142 which is in turn rotatably mounted 20 upon the pin 143 extending between the side plates of the feeder head casting 50, just in advance of the rear web 54. A spring 145 extends between a point on the upper portion of the block 142 and a pin 146 on the web 54 and tends 25 to urge the carrier block 142 and the blade 140 in a counterclockwise direction as viewed in Figure 4. In this direction of movement the blade 140 tends to contact with the rear end of the pile and to align the uppermost sheets. A rocking lever 148 is pivoted at 149 upon the wall 52 of the casting and is provided with an adjustable contact screw 150 at its lower end which is adapted to abut the upper end of the carrier block 142. The upper end 152 of the lever 148 bears upon 30 the rounded upper portion of one of the bifurcations of the carrier member 75. It will thus be seen that during the upward vertical movement of the carrier 75 the lever 148 will be rocked in a counterclockwise direction and it in turn will 35 rock the blade 140 in a clockwise direction about the pivot 143 and move it away from the rear end of the pile. The blade 140 is permitted to strike the pile under the influence of the spring 145 when the carrier 75 is lowered toward the 40 point where the suction gripper 20 engages the top sheet S. At this same time the sheets are being floated by the winding devices and the blade 140 serves to locate the sheets and maintain their alignment at their rear edges in this 45 position.

50 The winding devices for aiding in the separation of the sheets and floating them so that their forward feeding movement toward the conveyors is facilitated will now be described. Rearwardly 55 extending lugs 160 are provided on the transversely extending gauge bar 112 upon either side of the frame casting 50 and pivotally secured between these lugs as by means of the fulcrum pin 161 and the screw 162 is the blast nozzle supporting casting 163. This arrangement is best 60 shown in Figures 2, 3 and 4 of the drawings. This supporting casting 163 is provided with a partly cylindrical vertically extending portion 164 having a bore extending from end to end thereof 65 which is adapted to receive the tubular member 165 which is seated upon a coil spring 166 within the bore, the spring being in turn seated upon an internal shoulder 167 of the bore. The tubular member 165 is provided with a bifurcated projection 169 through which a threaded rod 170

passes, this rod being secured to the casting 164 and provided with a nut 171 for adjustably securing the member 165 in desired vertical positions against the compression of the spring 166. Extending through the member 165 is the cylindrical blast tube 175 which is closed at its upper and lower ends but is provided adjacent its lower end with a substantially T-shaped nozzle orifice 176 and may also be provided with a plurality of other orifices indicated in Figure 7 at 177. An 10 intake slot 178 is formed in the wall of the tube at an intermediate point within the casting 163 and communicates with a conduit 179 fitted within the hollow boss 180 in the casting. The tube 175 is adjustably secured to the tubular member 15 165 by means of the set screw 182. Upon the lower end of the tube there is secured as by means of the screw 185, the squared forwardly extending tubular member 186 which is provided 20 with a hood 188.

The main blast is delivered through this device preferably at a moderate substantially uniform rate for separating and floating the sheets and in the usual construction, a single blower or pump is employed for furnishing the vacuum for the suction gripper and the blast for winding the sheets. In this case, however, as clearly shown in the diagram in Figure 14, the intensity of the blast falls off to some extent when the grippers have made contact with the sheet and continues at this diminished pressure until the intake of the pump has been cut off from the gripper and, the sheet is released. This diminution of pressure is indicated by the inclined portion m of the curve l representing the pressure in the main blast device. As already pointed out it is not feasible to increase the blast through this main winding nozzle to any great extent throughout the operation of the feeder, but it has been found that the use of an auxiliary blast of greater intensity at a point just in advance of the gripping of the sheet by the suction device is highly beneficial in positively separating the adhering sheets and floating them during forward movement. The point at which this puff of additional blast is applied is indicated by the steep curve k in the diagram in Figure 14 and occurs between the points d and a in the cycle of movement of the sheet gripper.

55 This auxiliary blast is effected by the following mechanism. Attached to the main blast casting 163 at its lower rear portion is the small casting 190 which is secured thereto by means of the screw 191. This casting is best shown in Figures 3 and 4 of the drawings and is provided with a transverse bore through which is disposed the intermediate portion of the two-armed blast tube 195. The ends of the tube 195 are directed forwardly toward the rear edge of the sheet and are narrowed vertically as at 196 to provide a thin vertical jet of air. The intermediate portion of the tube 195 is provided with an opening for the admission of the air and this opening registers with the nipple 198 into which the coupling 199 is introduced for the connection of a 60 tubular conduit such as that indicated at 200 in Figures 1 and 16 of the drawings.

To provide this intermittent blast of air of relatively high pressure various devices may be employed. In accordance with one phase of the 70 present invention, however, use is made of the compressed air resulting from the cushioning or buffer action of the buffer cylinders and pistons of a reciprocating bed press to which the feeder may be applied. In Figure 16 of the drawings 75

such a press is indicated generally by the reference character R, the impression cylinder being shown at 205 and the reciprocating bed at 206. The sheet feeder with its conveying mechanism 5 C is disposed at one end of the press for feeding the sheets to the impression cylinder 205. The showing in this figure is quite diagrammatic and many parts of the press are omitted for the sake of clearness of illustration. At one end of the 10 press there is secured a buffer cylinder 210 into which one of the pistons 211 secured as at 212 to the reciprocating bed is adapted to move at the end of the stroke of the bed. A corresponding cylinder of course is disposed at the opposite end 15 of the press for the same purpose. Leading from the bottom of the cylinder 210 is a pipe 215 which is connected by means of the flexible conduit 200 to the auxiliary blast device 195. Interposed in the pipe 215 is disposed a spring-pressed non-re- 20 turn valve 216 which is provided in order to prevent too great a drop in pressure in the buffers which would prevent them performing their cushioning function. However, sufficient opening of the valve is permitted to provide a strong puff of 25 air through the auxiliary blast nozzles to positively ensure the separation of the sheets. The arrival of the bed of the press at the end of its movement coincides with the time that the auxiliary blast is required and therefore no ma- 30 chine-operated synchronized air valves are necessary.

In Figure 17 of the drawings there is illustrated an alternative arrangement for supplying the air to the auxiliary blast nozzles 195 by the use of 35 a separate pump 220 which is independent of the vacuum and blast pump or blower utilized for the main winding devices and the suction gripper. A reservoir 221 may be provided for the compressed air supplied by the pump 220 and a valve 40 222 actuated from and synchronized with the feeder mechanism by means of an operative connection 224, permits a puff or blast of air to pass through the conduit 200, to the auxiliary blast element at the proper points during the cycle.

45 A further modification may be provided which may dispense with the separate auxiliary blast nozzle end which may be useful in some cases. This modification involves the provision of a substantially uniform moderate flow of air through 50 the main blast nozzle during most of the cycle of said operation and this same blast may be increased in intensity at the proper point just prior to gripping the sheet, by any suitable means. For example, a regulated supply of compressed 55 air may be provided and controlled by a partly open valve and this valve may be moved to wide open position momentarily to provide the intermittent added impulses.

Having thus described the invention, what is 60 claimed as new and desired to be secured by Letters Patent is:

1. A sheet feeder of the class described comprising, in combination, means for seizing and forwarding the successive top sheets of a pile, 65 means for delivering a stream of air against the edge of the pile to wind the same, means for varying the intensity of said stream during the cycle of operation of the feeder, whereby the intensity of the stream is increased for a short 70 period during the movement of the first named means to seize the sheet.

2. A sheet feeder of the class described comprising, in combination, means for seizing and forwarding the successive top sheets of a pile, means 75 for delivering a continuous stream of air at a

moderate velocity against the rear edge of the pile during the entire separating and feeding cycle, means for delivering an intermittent auxiliary blast of air of relatively high intensity and short duration against said edge. 5

3. A sheet feeder of the class described comprising, in combination, means for seizing and forwarding the successive top sheets of a pile, means for delivering a continuous stream of air at a moderate and comparatively uniform velocity 10 against the rear edge of the pile during the entire separating and feeding cycle, means for delivering an intermittent auxiliary blast of air of relatively high intensity and short duration against said edge, once during each cycle of movement 15 and just prior to the time the first named means seizes the sheets.

4. A sheet feeder of the class described comprising, in combination, a suction gripper, means for causing the suction gripper to operate through 20 successive sheet separating and feeding cycles upon the pile of sheets, means for delivering a continuous stream of air of moderate velocity against the rear edge of the pile, said means including a pneumatic pump which is also used to 25 provide the source of vacuum for the suction gripper, means for delivering an auxiliary blast of air of relatively high intensity and short duration against said rear edge just prior to the time when the suction gripper seizes a sheet, and 30 a separate source of compressed air for said auxiliary blast.

5. In an apparatus of the class described, in combination, a machine for operating upon sheet material, said machine including a reciprocating member, and pneumatic buffers for cushioning 35 said member, a device for feeding sheets to said machine from a pile, said device including means for seizing, separating, and forwarding the successive top sheets from the pile, winding means 40 for assisting the separation and forwarding of said sheets, and means for transmitting blasts of air to said winding means from said pneumatic buffers. 40

6. In an apparatus of the class described, in combination, a printing press of the reciprocating bed and cylinder type, buffer cylinders on said press for cushioning the movement of said bed, pistons carried by said bed and adapted to move in said cylinders and compress air therein, 50 a device for feeding sheets to said machine from a pile, said device including means for seizing, separating, and forwarding the successive top sheets from the pile, winding means for assisting the separation and forwarding of said sheets, 55 said winding means including a jet for delivering a continuous main blast of air against the rear edge of the pile, and an auxiliary jet for delivering intermittent blasts of air of greater intensity and short duration against said edge and 60 timed in accordance with the cushioning shocks of said press bed, and means for placing said auxiliary jet in communication with at least one of said buffer cylinders.

7. The method of separating and feeding the 65 successive top sheets from a pile, which comprises directing a blast against an edge of the pile to loosen a plurality of the uppermost sheets thereof, and increasing the intensity of the blast momentarily to insure the separation one from 70 the other.

8. The method of separating and feeding the successive top sheets from a pile, which comprises seizing the successive top sheets of the pile adjacent their rear edges, and mechanically lifting 75

and forwarding them, directing a continuous blast of air against the rear edge of the pile to assist the separating and forwarding operation, and directing intermittent blasts of air of increased intensity and of short duration against said rear edge once during each cycle of mechanical separating and forwarding movement and at a time just prior to the seizing of the successive sheets.

9. In a sheet feeding apparatus of the class described, a winding device comprising, in combination, a hollow casing, means for adjustably mounting said casing upon a feeder head, a sleeve member resiliently received within said casing, means for adjusting the vertical position of said sleeve with respect to the casing, a tubular member having a closed upper end and received within said sleeve member, means for adjustably clamping said tubular member to said sleeve member, a passageway in said casing in communication with the hollow interior thereof and with a source of air under pressure, an elongated opening in the wall of said tubular member adapted to register with said passageway in all 25 of its adjusted positions, and a nozzle orifice adjacent the lower end of said tubular member directed toward said pile.

10. A winding device as set forth in claim 9 in which a horizontally disposed tubular element is carried by the lower end of said tubular member and surrounds the blast orifices thereof, and a hood is provided above the outlet end thereof.

11. In a sheet feeder of the class described, a winding device which comprises a main blast nozzle assembly including a supporting casing, a supplemental casing carried thereby and provided with an auxiliary air blast nozzle, and independent means for supplying air to said nozzles.

12. In a sheet feeder of the class described, a winding device which comprises a main blast nozzle assembly including a supporting casing, a supplemental casing carried thereby and provided with a substantially U-shaped tubular member having its ends directed toward the pile of sheets, and its intermediate portion received within said supplemental casing, an opening in said intermediate portion registering with an inlet opening in the casing, and compressed air connections communicating with said opening.

13. In a sheet feeder of the class described, a suction gripper movable through successive sheet separating and feeding cycles above the pile of sheets, a main blast nozzle adapted to supply a continuous stream of air under moderate pressure against the rear edge of the pile to assist in the separating and forwarding operations, a pneumatic pump having its intake connected with said suction gripper and its outlet connected with said blast nozzle, an auxiliary blast nozzle for intermittently directing puffs of air of higher pressure against the pile, a pump for supplying this auxiliary air and valve means synchronized with the operation of the suction grippers for admitting this air to the auxiliary nozzle at timed intervals.

14. In a sheet feeder of the class described, in combination, suction gripper mechanism for seizing, separating and forwarding the successive top sheets from a pile, said mechanism comprising a single flexible suction cup disposed above the rearward portions of said sheets and adapted to be brought into gripping contact therewith, means for guiding and forwarding the front

edge of each sheet, the arrangement being such that contact of the front edge of a skewed sheet with said last named means will cause the sheet to swivel to squared position due to the flexibility of said cup.

15. In a sheet feeder of the class described, in combination, suction gripper mechanism for seizing, separating and forwarding the successive top sheets from a pile, said mechanism comprising a single flexible suction cup disposed above the rearward portions of said sheets and adapted to be brought into gripping contact therewith, feed and drop rolls for guiding and forwarding the front edge of each sheet, the arrangement being such that contact of the front edge of a skewed sheet with said rolls upon entering the same will cause the sheet to swivel to squared position due to the flexibility of said cup.

16. In a sheet feeder of the class described, in combination, a feeder head including an oscillating suction gripper, and means for swinging said gripper upwardly and rearwardly and then forwardly to separate and forward the successive top sheets individually from the pile, pile guides disposed at the upper rear edge of the pile where- 25 by the edges of the sheets are buckled to some extent upon their upward and rearward movement to aid in the separation of adhering upper sheets.

17. In a sheet feeder of the class described, in combination, a feeder head including an oscillating suction gripper, and means for swinging said gripper upwardly and rearwardly and then forwardly to separate and forward the successive top sheets individually from the pile, a movable 35 tamping member disposed behind the pile and adjacent the rear edges of the uppermost sheets of the pile and adapted to intermittently tap said edges to maintain the vertical alignment of said sheets on the pile.

18. The arrangement set forth in claim 17 in which includes means operated by contact with the gripper mechanism during the movements of the latter for actuating the tamping member.

19. The arrangement set forth in claim 17 in which there are provided means for actuating said tamping mechanism in synchronism with the gripper mechanism, the actuating means being so timed that the taps are administered at approximately the time that the gripper seizes 50 the top sheet.

20. In a sheet feeder of the class described, in combination, a feeder head including an oscillating suction gripper disposed adjacent the longitudinal center line of a pile of sheets to be fed, 55 and means for swinging said gripper upwardly and rearwardly and then forwardly to separate and forward the successive top sheets individually from the pile, pile guides disposed at the upper rear edge of the pile and spaced laterally 60 from the suction gripper, whereby the edges of the sheets are buckled both laterally and longitudinally to some extent upon their upward and rearward movement to aid in the separation of adhering upper sheets.

21. A sheet feeder comprising, in combination, a pile supporting frame, a feeder head supported by said frame and carrying mechanism for operating above the pile to seize the successive top sheets, lift them, and move them forwardly from 70 the pile, said mechanism comprising a lever fulcrumed in said head for rocking movement in a vertical plane, a carrier member pivotally suspended from said lever, a gripper element carried by said carrier member, means for rocking said 75

lever and moving said carrier member through a sheet feeding and return cycle, and cooperating guide abutments formed respectively on the carrier member and the feeder head for confining the carrier member to a definite path of movement during at least a portion of its cycle.

22. A sheet feeder comprising, in combination, a pile supporting frame, a feeder head supported by said frame and carrying mechanism for operating above the pile to seize the successive top sheets, lift them, and move them forwardly from the pile, said mechanism comprising a lever fulcrumed in said head for rocking movement in a

vertical plane, a carrier member pivotally suspended from said lever, a gripper element carried by said carrier member, means for rocking said lever and moving said carrier member through a sheet feeding and return cycle, which cycle includes a downward and an upward movement, a jogger blade for the rear edge of the pile pivoted on said head, and operative connections between said jogger blade and said carrier member for actuating the former in time with the movements of the latter. 5 10
